United States Patent Office

Des. 220,628
Patented May 4, 1971

220,628

HOLDER FOR ATTACHMENT TO A TELEPHONE OR THE LIKE

Robert T. Crew, 3871 Gadsden Road,
Jacksonville, Fla. 32207

Filed Sept. 2, 1969, Ser. No. 18,945

Term of patent 14 years

Int. Cl. D14—99; D20—02

U.S. Cl. D26—14

FIG.2

FIG.6

FIG. 1 is a rear perspective view of a holder for attachment of a telephone, showing my new design;

FIG. 2 is a rear elevational view thereof;

FIG. 3 is a front elevational view thereof;

FIG. 4 is an end elevational view thereof;

FIG. 5 is a top plan view thereof; and

FIG. 6 is a cross-sectional view taken along line 6—6 of FIG. 1.

I claim:

The ornamental design for a holder for attachment to a telephone or the like, substantially as shown.
